UNITED STATES PATENT OFFICE.

ANDREW G. BRANDT, OF SCRANTON, PENNSYLVANIA.

DESIGN FOR A WHIRLIGIG.

SPECIFICATION forming part of Design No. 23,444, dated July 10, 1894.

Application filed June 5, 1894. Serial No. 513,589. Term of patent 3½ years.

To all whom it may concern:

Be it known that I, ANDREW G. BRANDT, a citizen of the United States, residing at Scranton, in the county of Lackawanna and State 5 of Pennsylvania, have invented a new and original Design for Whirligigs, of which the following is a specification.

The invention relates to a new and original design for whirligigs.

10 The object of the present invention is to provide an ornamental and attractive design for whirligigs; and the essential feature resides in a whirligig provided, at opposite sides, with a representation of a face, and having between the faces a mouth.

15 In the drawings: Figure 1 is a perspective view of a whirligig showing my new and original design. Figs. 2 and 3 are elevations of the same, showing different sides thereof.

20 Fig. 4 is a transverse sectional view of the whirligig.

Similar numerals of reference indicate corresponding parts in the several figures of the drawings.

Referring to the drawings, 1 designates the 25 body of a whirligig, provided, at opposite sides, with a representation 2 of a face, and having below the faces and between the same a mouth 3. Each face consists of a pair of eyes, a nose, and bulging cheeks, and the 30 mouth 3 being arranged between the faces, which are laterally elongated, serves for both of them.

It will be apparent that the whirligig presents an appearance which is ornamental and 35 attractive.

What I claim is—

The design for a whirligig herein shown and described.

In testimony that I claim the foregoing as 40 my own I have hereto affixed my signature in the presence of two witnesses.

ANDREW G. BRANDT.
